UNITED STATES PATENT OFFICE.

ROBERT W. SCOTT, OF BOSTON, MASSACHUSETTS, ASSIGNOR TO SCOTT & WILLIAMS, INCORPORATED, OF BOSTON, MASSACHUSETTS, A CORPORATION OF MASSACHUSETTS.

SEAMLESS STOCKING.

1,233,714.

Specification of Letters Patent. Patented July 17, 1917.

Application filed November 2, 1915. Serial No. 59,315.

To all whom it may concern:

Be it known that I, ROBERT W. SCOTT, a citizen of the United States, and resident of Boston, in the county of Suffolk and 5 State of Massachusetts, have invented new and useful Improvements in Seamless Stockings, of which the following is a specification.

My invention relates to circular knit or 10 seamless stockings having therein an imitation of some of the characteristic appearances of straight or flat-fashioned and seamed stockings.

The improvements of recent years in the 15 manufacture of circular knit seamless stockings have made them desirable articles of wear, but there still exists in the minds of some conservative purchasers a habit of choice in favor of the type of stocking having a seam at the back of the leg, which 20 prejudice is not based upon any present advantage or merit in the seamed stockings, however great such advantage may have been at past times. Unthinking purchasers 25 still depend upon superficial characteristics of the once superior sort of stocking to indicate to them a desirable article of purchase, without examining the stocking for the other structural features upon which a more 30 intelligent choice might be based. Such persons usually prefer, when they can be induced to make a decision on their respective merits, that type of stocking having no seam at the back, which has manifest advantages 35 as an article of wear. The existence of a large body of prejudice of this sort in the minds of the public unfairly militates against the sale of circular knit articles of hosiery. One purpose of my present invention is to provide in such hosiery an 40 imitation of the superficial appearance of the stockings of the other type, so that circular knit stockings made according to my invention will not be unfairly associated in 45 the minds of such purchasers with a crude and inferior class of goods, but may be taken upon their relative merit as garments.

One of the appearances, the absence of 50 which leads the uninformed public to believe the stocking is an inferior stocking, is a mark at the back of the leg incidental to making on a flat-fashioning or straight machine, caused by the transfer of loops of one wale to loops of an adjacent wale. In the

usual article these marks occur at the back 55 of the leg above the ankle, on either side of the seam marking the back central line of the stocking. When finished for sale, such full fashioned stockings are folded on the line of the seam, and the mark of these 60 transfers is conspicuous and distinctive.

I will now describe a seamless stocking having an imitation of such marks. In the accompanying drawings,

Figure 1 is a side view of a stocking as 65 folded when finished and ready for sale;

Fig. 2 is an enlarged detail of the fabric; and

Fig. 3 is a back view of the tapered part 70 of the leg.

The stocking 1 shown may have, in common with other circular knit articles of hosiery, the same number of needle-wales throughout, but the fabric by reason of changes in the length of stitch or the kind 75 of yarn or otherwise is made permanently wider at the calf of the leg 2 than at the ankle 3, the fabric tapering between from one width to the other width.

At the back of the leg and at the location 80 of this taper and preferably in the same needle wales 4 lying a fixed distance from and on each side of the central back needle wale 5 on which the stocking is folded when finished and ready for sale, I form during 85 manufacture marks 6, preferably separated as shown, of a different texture from the remainder of the fabric, as made for instance by transferring loops from one needle wale to an adjacent needle wale, or by making 90 a draw-stitch or group of draw-strokes, or by a tuck-stitch extending over two or more courses. I prefer the latter structure, which as illustrated in Fig. 2, may be made by accumulating loops or failure to cast off 95 during three or four courses with the result of showing enlarged loops 7, 8, and eyelet holes 9, 10, 11 and 12 at the surface of the fabric.

In some cases I associate the imitation 100 narrowing mark so formed with any of the well-known mock-seam structures formed at the central wales at the back of the leg, for instance by omitting a needle as illustrated at 14 in Fig. 2.

What I claim is:

1. A seamless stocking having therein at the back of the leg a structural variation of

the knit fabric of which it is composed, imitating the narrowing marks occurring in seamed or other narrowed stockings.

2. A seamless stocking having a tapered leg having the same number of needle wales therein throughout and separated structural marks occurring in the same needle-wale on each side of and near the central back line of the stocking at the tapered portion only
10 thereof.

3. A seamless stocking having a tapered leg, a mock-seam at the back of the leg, and

separated marks imitating transferred narrowings at either side of the mock seam in said tapered portion.

4. A seamless stocking having a tapered leg and tuck-stitch marks separated in the direction of the length of the stocking occurring in the same needle-wale on each side of the central back line of the stocking at 20 the tapered portion.

Signed by me at Boston, Massachusetts, this 30th day of October, 1915.

ROBERT W. SCOTT.
